INVENTOR.
FRANK E. SINCERE.

BY *Charles H. Wilson*
ATTORNEY.

UNITED STATES PATENT OFFICE.

FRANK E. SINCERE, OF MOUNT VERNON, NEW YORK.

UMBRELLA.

Application filed June 6, 1922. Serial No. 566,402.

This invention relates to umbrellas, and one of the objects of the invention is to provide an umbrella of unusually inexpensive construction which is intended for use for 5 emergency purposes.

Another object of the invention is to provide an umbrella in which the supporting ribs are formed as an integral part of the cover, the cover then being mounted on the 10 usual stick and being capable of distension or collapse in the ordinary manner.

Another object of the invention is to provide an umbrella of inexpensive construction in which the cover is formed of a suitably 15 treated fabric constructed of a plurality of gores in the ordinary manner, these gores being united along their overlying edges by cementing or pasting, and being provided with ribs which are attached to the cover 20 throughout their length in the operation by which the cover is formed.

Another object of the invention is to provide an umbrella having a cover of an inelastic material and made up of a plurality of 25 gores, these gores being so preformed as to give the cover its ordinary dome-like shape when the cover is distended, there being also provided a plurality of ribs which form an integral part of the cover.

Another object of the invention is to provide an umbrella having a cover formed of an inelastic material constructed of a plurality of gores, these gores being preformed so 35 that when held taut, the cover will have the usual dome-like form with an indented peripheral margin, the cover also being provided with ribs forming an integral part of the same, such ribs being disposed in the cover along the lines of union of the gores.

Other objects and aims of the invention, more or less specific than those referred to above, will be in part obvious and in part 40 pointed out in the course of the following description of the elements, combinations, arrangements of parts and applications of principles constituting the invention; and the scope of protection contemplated will be indicated in the appended claims.

In the accompanying drawing, wherein I 50 have shown several embodiments of my invention:

Figure 1 illustrates an umbrella constructed after my new and improved methods with a part of the top broken away;

Figure 2 is a cross-sectional view of the detail of the cover mounting;

Figure 3 is a top-plan view of the parts illustrated in Figure 2;

Figure 4 is a cross-sectional view of a modified form of cover mounting showing the 60 cover in extended position;

Figure 5 is a view similar to Figure 4 showing the cover collapsed;

Figure 6 is a view in perspective showing the means by which the ribs are attached to 65 the stretchers;

Figure 7 is a detailed perspective view of the attaching means;

Figure 8 is a view in perspective of a detail of one form of rib construction;

Figure 9 is a perspective view in detail 70 showing the rib in place in the cover;

Figure 10 is a view similar to Figure 9, but showing another form of rib construction;

Figure 11 is a view in cross-section showing the means by which the stretchers are 75 mounted on the runner; and

Figure 12 is a view in perspective showing the runner with the attached stretchers.

With reference now to the drawings in 80 which similar reference characters refer to similar parts throughout the views thereof, the reference character 1 designates a stick provided with a handle 2 of any form. This stick may be constructed of wood or light 85 metal in the usual manner.

Near the end opposite the handle is to be mounted a cover 3 which is to be constructed preferably of fabric.

The cover is formed of a fabric or of a 90 paper material which has been treated either to be water-shedding or water-tight. This fabric may be of inelastic material or may be made inelastic in the water-shedding or water-proofing process. As is shown, the 95 top is composed of a plurality of gores 4, 4, these gores being constructed in the manner set forth in the application referred to. The gores are to be formed by cutting from a sheet of material and are given a shield-like 100 form for purposes presently to be set forth.

It will be understood that, owing to the inelasticity of the fabric, it is impossible to provide a cover formed of triangularly designed gores, which are cut on the bias and caused 105 to assume the usual form by stretching when the top is raised. On account of the inelasticity of the fabric, the gores are given the shield-like form with indented margins 5 which are to lie along the periphery of the finished top, and the overlapping sides of the 110 gores are formed along a slightly outwardly

bowed line so that the top will assume a dome-like form when held taut.

As has previously been explained, one of the objects of this invention is to provide 5 a cheap umbrella which is to be used for emergency purposes, the umbrella being sold at a moderate price and being intended to protect the user only on one or two occasions. I preferably form the cover, therefore, of 10 treated paper and desire to eliminate the usual frame construction in which there is provided a plurality of ribs supported by stretchers near their middle points, the other end of these stretchers being attached 15 to a runner which may be moved along the stick so as to raise and lower the cover. To this end I have provided a construction in which there are used ribs formed of steel wire of such size and composition as to have a 20 slight amount of elasticity. These ribs are to be incorporated in the top when the latter is formed of the united gores, and to this end I provide a form similar to that of the extended top on which the gores are to be laid 25 with their edges overlying.

As I have explained, the ribs are to be united to the top along their entire length and I show two methods by which such a mounting for the ribs may be provided. In 30 the method illustrated in Figure 8 I have found it desirable, in some instances, to lay the wire 6, as has been explained, between strips 7 and 8 made of paper coated with an adhesive material. The wire 6 is laid centrally of these strips, which are then united 35 so as to provide the construction shown in Figure 8. It will there be noted that the upper strip of paper 7 is laid flat, while the strip 8 has a portion 9 which extends about 40 the wire. The wire provided with its paper coating is then cut off in such lengths as may be desired, in accordance with the size of the top which is to be used.

The rib, which may be designated as 10, is 45 then laid in the required position on the form, and the upper surface of the strip 9 is coated with an adhesive material. One of the gores 50 11 (see Figure 9) is then laid with its marginal edge overlying the strip 7, being united thereto by the adhesive material. The adjacent gore 12 is then united along its marginal edge to the upper surface of the gore 11, and this process is repeated until there 55 is formed a unitary structure composed of a plurality of gores, along the united margins of which are provided ribs formed after the manner illustrated in Figure 8.

I have found that, by providing ribs enclosed in paper strips, it is possible to use a 60 light paper for cover purposes. However, it is possible in many instances, to omit the reinforcing strips illustrated in Figure 8 and to construct the top by laying a gore as 11 on the form (see Figure 10), then placing the 65 wire ribs in position along the marginal edge

of the gore and uniting the adjacent edge of the gore 12 in overlying position on the gore 11, the rib 6 being held in position along this line of union and between the edges of the gores. 70

Either construction is suitable for the purpose, or else I may reinforce the edge of one gore, as, for instance, the gore 11, by pasting thereon a strip of paper similar to that illustrated in Figure 8. The rib is then to be held 75 between the paper and the united edges of the gores, the paper simply providing an additional reinforcement.

It is clear that there must be provided a central aperture through which the stick 1 80 is to project, and disposed on either side of the cover adjacent this aperture I provide reinforcing members 13 and 14, which may be made of any suitable material in the required annular form. I have found a light cloth 85 will be suitable for this purpose, and it will be noted that the inner marginal edges of the members 13 and 14 will project beyond the edges of the cover and will lie closely adjacent the surface of the stick. 90

In order to mount the top on the stick, I use a construction in which the ends of the ribs are not pivotally attached to the stick as is usually the case. To this end I provide a collar 15, which is crimped or otherwise fastened to the stick at the required point. The stick with this collar in place is inserted through the aperture in the top, and there is then forced over the outer end of the stick a second collar 16. The latter will be seen 100 to have a relatively wide flared bending so that the marginal edge 17 will contact with the reinforcing member 13 at a point a slight distance beyond the inner end of the ribs. 95

In Figure 2 the relative position of the various parts is clearly set forth, but it will be understood that the collar 16 will be forced tightly in position before being firmly attached to the stick. In this way there is provided a clamp by means of which the edges 110 of the reinforcing members are held in position relative to the stick. 105

As a modified form of construction for the purposes just described, I have found it satisfactory to omit the collar 15, but to provide 115 an outer collar 18 in the flared form, having its marginal edge 19 extending inwardly as illustrated in Figure 4. I then provide the ribs with turned up ends 20, these ends being bent at a right angle and being so disposed 120 that the ends project a slight distance into the bell of the collar 18. When the top is extended, the ribs will keep the position illustrated in Figure 4, being forced outwardly by the stretchers, which will presently be described. 125

The reinforcing members 13 and 14 will thus hold the inner edges of the top firmly in position against the collar 18. When the top is collapsed, however, the bent ends of 130

the ribs will be turned so as to lie interiorly of the bell. (See Figure 5.) In this way the top is prevented from becoming detached from the collar when the umbrella is closed.

5 In order that the top may be raised, in the usual manner, I provide a runner 21 which may be stamped from sheet metal to the form illustrated in Figures 11 and 12. This runner is formed as a collar from which there extends a flange provided with a plurality of apertures, these apertures corresponding in number to the number of ribs. The runner is to be mounted on the stick and the central aperture therethrough will correspond to the 10 diameter of the stick. Positioned in the apertures of the runner are a plurality of stretcher members 22, there being one for each rib. These stretcher members 22 are constructed of suitable wire and have a hook 23 15 on the end, which engages in the runner. At the outer ends, the runners are provided with similar hooks 24 which are to engage in rings 25, which are mounted on the ribs. These rings, which are here illustrated simply as 20 one convenient method for attaching the runners to the ribs, are formed of wire somewhat in the shape of a stirrup having a straight portion which is held between strips 26 and 27 of paper or some similar material, the strips 25 26 and 27 being then pasted, cemented or united in any other similar manner to the ribs at the desired point. The stick is provided with a customary stop member 28, against which the runner is to be held when the umbrella is opened, and there is also provided a spring catch 29 by which the umbrella may 30 be held.

It will thus be seen that I have provided an umbrella of extremely inexpensive construction which is entirely satisfactory for the purposes outlined. As has been set forth, the top may be formed with the ribs integrally disposed therein and this top may be readily mounted in place on the stick and the 45 stretchers attached thereafter.

Under ordinary circumstances, it is customary to provide a frame having a plurality of ribs which are permanently attached to the stick and the top is supported on and attached 50 to these ribs. I have eliminated this feature of umbrella construction and have provided a device which may be constructed with a paper top which is thoroughly satisfactory for protection against rain.

55 I have found that the rib and stretcher construction herein set forth will be strong enough to withstand any wind pressure to which the usual form of umbrella may be exposed and furthermore, the umbrella may 60 be constructed with the elimination of a great many manufacturing steps which results in high labor costs.

While I have illustrated various methods of mounting the ribs in the cover and also

of mounting the cover on the stick, it is to be understood that I do not desire to limit myself to the constructions shown which are here put forward primarily for purposes of illustration. It is obvious that other constructions are possible coming within the broad idea of disposing the ribs within the top and holding the top in place on the stick without permanent attachment of the ribs to the stick. It is my desire, therefore, that the constructions shown may be considered merely illustrative and not in a limiting sense, and the scope of the protection desired is set forth in the following claims.

Having thus described my invention, what I claim as new and desire to secure by Letters Patent is:

1. As an article of manufacture, an umbrella provided with a top composed of a plurality of gores of substantially inelastic material united along their adjacent edges and provided with a plurality of metallic reinforcing ribs encased in reinforcing strips of relatively stiff and rigid material as compared with a textile fabric, and fastened to said top along the line of union of said gores. 90

2. An umbrella of the class described comprising, in combination, a stick having a pair of spaced collars disposed near one end thereof, a top comprising a plurality of gores of relatively stiff and rigid material so joined as to provide definite elongate pockets along the lines of union of said gores, said top being also provided with a plurality of reinforcing members permanently secured in said pockets, said top when thus constructed having a central aperture, and annular reinforcing members disposed on either face of said top about said aperture, said stick projecting through the aperture in the said top, and said annular reinforcing members being held between said 100 collars. 95

3. An umbrella of the class described comprising, in combination, a stick, a cover having a plurality of reinforcing ribs disposed therein, said ribs carrying loops immediate 110 their ends, stretcher means connected to said loops whereby to raise said cover, and means to hold said cover on said stick, the ends of said reinforcing ribs adjacent said stick being free of said stick. 115

4. An umbrella of the class described comprising, in combination, a stick, a top constructed of a plurality of gores provided with metallic reinforcing ribs disposed along the lines of union thereof, said reinforcing ribs being provided at their inward ends with bent portions, stretcher means mounted on said stick to raise and lower said top, and a bell-shaped collar with inwardly extended edges mounted on said stick and having a portion adapted to engage the bent portions of said reinforcing ribs to prevent movement of said ribs radially of said stick when said top is 120 125

raised and to prevent movement of said ribs longitudinally of said stick when said top is lowered.

5. An umbrella of the class described comprising, in combination, a stick, a top formed of a plurality of gores and having metallic reinforcing ribs disposed therein along the lines of union of said gores, the inner ends of said ribs being bent at an angle, stretcher means mounted on said stick and engaging said ribs whereby to raise and lower said top, and a flared collar having an inwardly bent margin defining the aperture therein, the marginal edge of said collar being disposed to engage the bent portion of said ribs whereby to hold said top on said stick.

6. An umbrella of the class described comprising, in combination, a stick, a top con-

structed of a plurality of gores united along their adjacent edges, and having metallic ribs disposed therein along the line of union of said gores, the inner ends of said ribs being angularly bent, a plurality of stretchers having one end mounted in a runner on said stick, the other end being attached to said ribs, reinforcing members disposed on either face of said top, and centrally thereof, and a flared collar disposed on said stick and having a portion lying in contact with one of said reinforcing members and another portion engaging the bent ends of said ribs whereby to prevent the movement of said top along said stick.

In testimony whereof, I affix my signature.

FRANK E. SINCERE.
